TRACK GRINDER

Henry H. Talboys, Milwaukee, Wis., assignor to
Nordberg Manufacturing Co., Milwaukee, Wis.,
a corporation of Wisconsin

Application November 11, 1932, Serial No. 642,160

14 Claims. (Cl. 51—178)

My invention relates to an improvement in track or rail grinding mechanisms and their method of use. One object is the provision of a light efficient readily operated track grinder. Another object is the provision of a track grinder having a single power plant mounted thereon and a plurality of track grinding elements alternately driven from said single power plant. Another object is the provision of improved guiding means for a guided track grinding element. Another object is the provision of improved means for adjusting and adjustably supporting a track grinding element. Another object is the provision of improved means for manually moving the track grinder along the track. Another object is the provision of improved means for turning said track grinder to reverse or change its direction on a track. Another object is the provision of improved means for varying or controlling the level of the grinder element, when it is necessary to grind off uneven parts of opposed rail ends and when it is necessary to grind down the edges of apertures in the rail tops. Other objects will appear from time to time in the course of the specification and claims.

I illustrate my invention more or less diagrammatically in the accompanying drawings, wherein—

Figure 1 is a side elevation;

Figure 2 is a plan view;

Figure 3 is a section on the line 3—3 of Figure 2;

Figure 4 is a section on the line 4—4 of Figure 2;

Figure 5 is a section on the line 5—5 of Figure 2;

Figure 6 is a section on the line 6—6 of Figure 2;

Figure 7 is a section on the line 7—7 of Figure 2;

Figure 8 is a detail;

Figure 9 is a side elevation of the parts shown in Figure 8;

Figure 10 is a side elevation, similar to Figure 1, illustrating the operation of one means for varying or controlling the level of the grinding member;

Figure 11 is a similar view illustrating another method or means for controlling such level;

Figure 12 is a section on the line 12—12 of Figure 11;

Figure 13 is a detail of the level varying device shown in Figure 11;

Figure 14 is a side elevation illustrating a va-

riant form of manually moving the grinding device; and

Figure 15 is a section on the line 15—15 of Figure 14.

Like parts are indicated by like symbols throughout the specification and drawings.

Referring to the drawings, A generally indicates railroad ties upon which are mounted a plurality of rails A¹ A¹.

B is a longitudinally extending frame member at one side of the frame. Secured to the upper face thereof are bearing sleeves B¹ B¹ at opposite ends thereof. B² indicates a handle secured to one end of the frame member B, it being understood that a similar handle could if desired be positioned also at the opposite end. B³ generally indicates an irregular shaped frame member at the opposite side of the frame, which may include short end bars B⁴, beneath which are secured the bearings B⁵. The bars B⁴ are united by the angular member B⁶ and stiffening bars B⁷. The angular member B⁶ may be braced as by the bar B⁸. The bars B⁴, B⁶, B⁷ and B⁸ are preferably of square tubing and may be welded together. The cross members B and B³ are joined by means of two parallel bars B⁹, B¹⁰ which are braced by means of cross members B¹¹, B¹², B¹³ and B¹⁴. The above described members comprise a main frame which is supported upon flanged wheels B¹⁵ and may be moved along the rails A¹. Referring to Figures 2 and 5 I have shown the wheels B¹⁵ mounted upon the transverse shafts B¹⁷ supported in the bearings B¹, B⁵. As illustrated in Figure 5, the set of wheels adjacent the cross member B are electrically insulated from the shafts by means of the washers and tapered sleeve B¹⁸ of insulating material, and may be fixed to the shafts. The wheels B¹⁵ upon the opposite end of the shafts may be mounted to be free to rotate about the shafts. One or both of the wheels adjacent the cross member B³ may be provided with a handle B²⁰ as shown in Figures 1 and 2, whereby the track grinder may be manipulated. Figures 14 and

15 illustrate a variant form of handle which may be in the shape of a ring B²¹, circular in cross-section and somewhat smaller in diameter than the rim of the wheel, said ring being spaced from and supported upon the wheel by means of the brackets B²².

Referring to Figures 1, 3 and 5, C, C, are a pair of track or guide members mounted upon the bars B⁹ B¹⁰ by means of the angle bars C¹, having locking pins C². The angle bars or clips are secured to the bars B⁹ B¹⁰ by means of bolts

C^3 , screw-threaded into nuts C^4 which are shown as welded to spacing members C^5 for ease of assembly. Each guide member C is provided with a V-shaped groove C^8 . Positioned within said grooves are one or more balls or rollers C^6 . Referring to Figure 5, I have illustrated two of such balls C^6 which may be held in proper relation to each other by means of a spacing member C^7 .

- 10 Supported upon said balls or rollers are the track or guide members D having grooves D^1 which are engaged by the balls C^6 . Note that the balls engage the grooves of the track members at two points only, thereby reducing friction. The guide members D are mounted beneath a movable sub-frame generally indicated as D^2 . Identical means of mounting as employed for tracks C are used and as such lettered. Referring to Figures 4, 5, 8 and 9, the sub-frame D^2 comprises a pair of frame members D^3 to which the tracks D are secured. Welded or otherwise secured to the frame members D^3 are the reinforcing plates D^4 to which are welded spacing or tie channel irons D^5 and a bar D^6 .
 15 The members D^3 D^6 may be of square tubing as shown. Welded to the bar D^6 and one of the channel irons D^5 is a circular rod or tubing D^7 , adapted to be engaged between the V-shaped roller E and the roller E^1 , as illustrated in Figure 7. The roller E is mounted upon a fixed pin or bolt E^2 in the U-shaped bracket E^3 . The roller E^1 is held in frictional engagement with the rod D^7 as by the shaft E^4 mounted in the slidable bearing member or fork E^5 which is downwardly thrust by means of the spring E^6 , the tension of which may be adjusted by means of the adjusting nut E^7 upon the screwthreaded portion E^8 of the fork E^5 , the portion E^8 being positioned and guided in an aperture E^9 in the bracket E^3 . Likewise the shaft E^4 is guided in elongated apertures E^{10} in said bracket. The bracket E^3 is welded to a base plate E^{11} which is adjustably mounted by means of shims E^{12} and bolts E^{13} to the cross member B^{12} of the main frame. As above described the sub-frame D^2 is held in sliding relationship with the main frame by means of the circular rod D^7 and the grooves D^1 of the tracks D engaging the balls or rollers C^6 . In order to prevent displacement of the sub-frame and furthermore to eliminate unintended longitudinal movement of said frame and associated parts I provide a pair of friction rollers F , engaging the reinforcing plates D^4 as indicated in detail in Figures 3 and 5. Each roller is mounted upon a pin F^1 integral with the rod F^2 at right angles therewith. The rod F^2 is screwthreaded as at F^3 to receive the adjusting nuts F^4 which support a bearing sleeve F^5 slidably mounted in a tubular grinding member F^6 . F^7 indicates a bearing plate secured in the member F^6 which serves as a guide for the rod F^2 adjacent the pin F^1 . Compressed between the bearing plate F^7 and the sleeve F^5 is a spring F^8 , the tension of which may be varied by means of the adjusting nuts F^4 .
 20 Rotation of the rod F^2 is prevented by means of the slots F^9 open at one end, in which is slidably positioned the pin F^1 . The rod F^2 is provided with a handle F^{10} whereby the pin F^1 may be lifted out of the slots and the rod and associated roller may be rotated to clear the plate D^4 of the sub-frame D^2 .
 25 Welded to the lower flanges of the channels D^5 of the sub-frame are the split bearings G which include the removable caps G^1 and locking screws G^2 . Mounted for rotation in said bear-

ings are split bushings G^3 which are secured in any suitable manner to a bearing sleeve G^4 . The sleeve is apertured as at G^5 and counter-bored to receive the ball bearings G^6 in which is mounted a stub shaft G^7 . G^8 is a grease fitting for lubricating the bearings G^6 and G^9 indicates a packing ring. The stub shaft is screwthreaded at one end to receive a lock nut G^{10} ; the opposite end which may be of smaller diameter is connected by means of a flexible union G^{11} to an extension shaft G^{12} , which in turn is positioned within a driving sleeve G^{13} having a plurality of keys G^{14} adapted to engage opposed keyways G^{15} in the shaft G^{12} . As will be seen in Figure 4 the shaft G^{12} is slidably mounted in the driving sleeve G^{13} giving in effect a telescoping action. The driving sleeve G^{13} is journaled in roller bearings G^{16} in a bearing housing G^{17} which is secured as by the bolts G^{18} upon the cross member B^{12} of the main frame. G^{19} indicates a clutch shift lever mounted upon the transverse cross-bar B^3 adapted to operate the clutch G^{20} , one part of which is splined to the driven shaft G^{21} integral with the sleeve G^{13} , the opposite clutch member of which is secured upon the drive shaft G^{22} of any suitable internal combustion engine or motor, diagrammatically indicated as G^{23} . The motor may be mounted in any suitable manner upon the transverse frame members B , B^{14} and may be shielded as illustrated in Figures 2 and 6.

Referring to Figures 1, 3 and 4, the bearing sleeve G^4 is provided with a lug or arm G^{25} upon which is adjustably mounted a lug H^1 integral with the bearing member H . Adjustment is permitted by means of the slots H^2 in the lug H^1 , penetrated by the locking bolts H^3 . The bearing member is apertured as at H^4 and counterbored to receive the ball bearings H^5 in which is journaled the shaft H^6 . The ball bearings H^5 may be lubricated by means of the grease fitting H^7 . The shaft H^6 is reduced in diameter as at H^8 upon which is secured, by means of the discs H^9 and lock nuts H^{10} , threaded upon the screwthreaded end H^{11} of the shaft, any suitable grinding wheel H^{12} . H^{13} indicates a pulley keyed to the shaft H^6 , which is actuated by means of one or more belts H^{14} which pass about the pulley H^{15} keyed to the driven shaft G^7 . H^{16} indicates a semi-circular guard or housing for the grinding wheel.

In order to raise and lower the grinding wheel, provision is made for rotating the bearing sleeve G^4 and associated parts about an arc, the axis of rotation being the shaft G^7 .

Referring to Figures 1, 2, 4 and 6, J indicates an extension sleeve, which may be secured upon the bearing sleeve G^4 as by the screws J^1 . The sleeve J is provided at its outer end with a flange upon which is mounted as by the bolts J^2 a gear segment J^3 which meshes with a pinion J^4 upon the shaft J^{55} . J^6 indicates a bearing sleeve or tubing welded upon the upper flanges of the channels D^5 on the sub-frame D^2 in which the shaft J^5 is mounted. The bearing sleeve J^6 is slotted as at J^7 about the pinion J^4 . The shaft J^5 is actuated by means of the hand wheel J^8 . In order to prevent unintended rotation of the shaft, I have provided friction blocks J^9 bearing against the periphery of the hub of the wheel J^8 and portion of the sleeve J^6 . The amount of friction of the springs J^{10} about the bolts J^{11} compressing the blocks J^9 may be adjusted by means of the nuts J^{12} as illustrated in Figure 9.

It is essential to hold the shaft H^6 supporting the grinding wheel H^{12} rigid in its adjusted posi-

tion. In order to prevent any lost motion between the gear teeth of the pinion J^4 and gear segment J^3 I provide one or more compression springs J^{15} with one end anchored on a rod J^{16} welded to the sub-frame D^2 . The opposite ends are fastened to angle clips J^{17} which are secured to the lug or arm H^1 . Some of the bolts H^3 may be utilized for fastening.

Referring to Figures 1, 2, 4 and 6, I have illustrated driving means for a further grinding wheel. Mounted upon the driving sleeve G^{13} is a pulley K about which passes the belt K^1 adapted to drive the pulley K^2 secured to the shaft K^3 . K^4 indicates a bearing sleeve for said shaft which is welded to one or more arms K^5 pivoted as at K^6 to any suitable abutments K^7 on the main frame. One of the arms extends beyond the pivot as shown in Figure 6, at which end a spring K^8 is attached. The opposite end of the spring is secured to a chain K^9 which may be fastened to any suitable hook or slotted abutment K^{10} on the frame member B^9 . The function of the spring and chain are to rotate the arm K^5 clockwise and to tighten the belt K^1 upon the pulleys K , K^2 , which establishes a driving connection. The pulley K^2 and associated parts are so positioned as to rotate counter-clockwise about the pivot when the chain K^9 is released, thereby loosening the belt K^1 and breaking the driving connection. In order to retain and support the belt K^1 in said position I have provided a guide or retaining member K^{11} secured to one of the arms K^5 and a fixed guard member K^{12} mounted on the main frame. As illustrated in Figures 1 and 2 the shaft K^3 is utilized to drive a flexible shaft K^{13} in a casing K^{14} . The opposite end of the flexible shaft may through any suitable driving connection operate a grinding wheel K^{15} which may be provided with a housing K^{16} having one or more handles K^{17} . K^{18} indicates a supporting bracket for the flexible shaft.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic, rather than as limiting me to my specific showing.

For example, whereas in the drawings, I illustrate the wheel H^{12} as lying in a plane generally parallel with the longitudinal extension of the rail I find that frequently in practice it is preferable slightly to tilt the axis of rotation of the grinding wheel so that as the grinding wheel of the grinder is moved across the intersection between two rail ends it will not drop into the space between the rails or tend to trough out or deepen the rails, but will grind in a substantially parallel plane level to the top of the rail. It is exceedingly desirable to avoid any beveling off of the rail ends as this merely accentuates the condition which the present apparatus is used to avoid.

The use and operation of my invention are as follows:

The track grinder generally consists of a main frame structure supported on flanged wheels upon a track and may be moved along the track by the handles B^2 . Provision is also made for fastening any suitable towing bar or handle to either one of the connecting abutments B^{25} with their associated pin or bolt. One set of wheels in contact with one of the rails may be electrically insulated from their respective shafts in order to prevent

any interference with the usual electrical signal system employed by railroads. Mounted for longitudinal movement upon the main frame is the sub-frame D^2 which is held in alignment and supported by the tracks C , D , with their respective balls or rollers C^6 , and by the extension tube D^4 supported between the rollers E , E^1 . Sufficient pressure upon the sub-frame structure D^2 is provided by means of the spring thrust roller E^1 and the friction rollers F bearing upon the plates D^4 above the grinder D , to eliminate unintended longitudinal movement of the frame after it has been adjusted. The friction of the rollers E^1 and F are adjustable. The sub-frame carries in bearings G , G^1 the sleeve G^4 which in turn supports in ball bearings the shaft G^7 . The arm G^{25} of the bearing sleeve G^4 carries the bearing member H which supports the shaft H^6 upon which is secured any suitable grinding wheel H^{12} . The shaft H^6 is driven by means of the pulley H^{13} actuated by the belts H^{14} about the driving pulley H^{15} which is keyed to the shaft G^7 . The belts H^{14} may be tightened about their pulleys in case of wear by means of the slots H^2 and locking bolts H^3 . The shaft G^7 is connected by means of a flexible coupling with the shaft G^{15} splined to the sleeve G^{13} which in turn is connected by means of the clutch G^{20} to the drive shaft G^{22} of any suitable motor or combustion engine. The bearing sleeve G^4 is provided with a gear segment J^3 in mesh with the pinion J^4 upon the shaft J^5 , which is rotated by means of the wheel J^8 . It will be seen from the drawings that by rotating the wheel J^8 the bearing sleeve G^4 is rotated and the bearing H which supports the shaft H^6 is swung about an arc, thus either lowering or raising the grinding wheel H^{12} , depending upon which direction the hand wheel J^8 is turned. To prevent lost motion between the gears, and furthermore to create sufficient friction to eliminate unintended movement of the grinding wheel after it has been set in position for grinding I provide the springs J^{15} which also assist in raising the grinding wheel structure.

It is a common occurrence that the rails A^1 wear unevenly especially where they are connected together. The surface may be built up again, as by welding, and is then ready for grinding. The operator may now position the grinder and by means of the hand wheel J^8 pull out if necessary the sub-frame assembly and place the grinding wheel H^{12} above the rail to be ground. Then by rotating the hand wheel clockwise he may lower the grinding wheel until it comes in contact with the metal to be ground off. He may now, either by means of the handle B^{20} , or rotating the wheel B^{21} on the flanged wheel B^{16} , guide the track grinder back and forth and thus grind off the surplus material of the rail. The grinding wheel may also be adjusted and lowered to grind off either side of the rail. The rotation of the grinding wheel is in the direction of the arrow in Figure 1. In order to protect the structure of the grinder adjacent the grinding wheel and particularly the flanged wheel in line with the spray of ground off particles, the grinding wheel is provided with a guard H^{16} and an additional wheel guard B^{26} is suspended in any suitable manner about the exposed flanged wheel B^{16} , to which some of the hot particles would adhere and destroy its true periphery which is very essential to produce a level surface of the rail.

Referring to Figure 10 I have illustrated a method of grinding a rail which has been worn into depression by the spinning wheels of loco-

- motives. The rail A^1 , having a depression M , is preferably ground away as indicated in dotted lines and marked as M^1 , so as to taper both ways forming a gradual incline from the depression 5 to the top of the rail. To facilitate this method of grinding I may employ a guiding member or bar M^2 , formed with inclined faces M^3 upon which one of the wheels B^{16} of the main frame is positioned as indicated. By moving the track grinder 10 to the left as shown in Figure 10 after the grinding wheel has been adjusted just to contact the surface of the rail A^1 , the grinding wheel may grind off the surface of the rail so as to obtain a contour similar to the inclined faces M^3 as 15 the grinding member M^2 .
- Another objectionable defect of tracks is adjoining rail ends of different heights, as illustrated in Figure 11. As shown, the rail N being of greater height than the rail N^1 may be ground 20 off as indicated in dotted lines and lettered N^2 , to form a long tapered surface towards the lower rail N . The taper may be very small, for example, it may be seven thousandths of an inch per inch. This grinding operation may be facilitated 25 by means of a guide member N^3 positioned on top of the rail N , having a tapered surface N^4 . Thus, by moving the track grinder to the dash and dot line position as illustrated in Figure 11, the rail N may be ground away as indicated at 30 N^2 . The guide member N^3 is preferably slightly curved as illustrated in Figure 13 when in inoperative position, its function being to bite into the rail at either end when the cross grinder is positioned thereupon. This prevents a tendency 35 to turn or dislodge the member N^3 during grinding. The guide member M^2 may be curved identically when in inoperative position.

In Figures 1 and 2 I have illustrated an additional independently handled grinder or cutter 40 K^{15} which may be used for grinding the edges of opposed rails for proper rail clearance. This grinder is driven by means of the flexible shaft K^{13} which may be actuated by means of the pulley K^2 . Driving connection is made by means 45 of the belt K^1 about the pulley K , which in turn is secured upon the driving sleeve G^{13} . The pulley K^2 may be rendered idle by disconnecting the chain K^9 on the spring K^8 which allows the arms K^5 to rotate counter-clockwise and thus loosens 50 the belt K about its pulleys. The motor G^{23} is adjusted to drive either grinding element. The cross grinder may further be provided with a tool basket P .

Should it be desired to repair the opposite rail, 55 the cross grinder may easily be turned upon a stand Q illustrated in dotted lines in Figure 6, which may be positioned upon a tie A beneath a socket Q^1 upon the cross grinder. It may then be raised by means of a screwthreaded member 60 Q^2 screwthreaded in the stand Q and one end seated in the socket Q^1 . After the cross grinder is sufficiently raised above the rails it may easily be rotated.

If the use of the grinding wheel K^{15} is not 65 desired, or if the cross grinder is moved along the track, the flexible shaft in the casing may be supported upon the grinder and one of the handles K^{17} may be utilized for attaching the grinding wheel K^{15} to any suitable bracket, preferably upon the frame member B^3 .

I claim:

1. In a track working machine, a frame adapted to span the rails of a track, rail engaging wheels at each side of said frame, a power source mounted on said frame, a grinding element and a

driving connection between said element and said power source, and a carriage for said grinding element, said carriage being mounted for movement upon said frame, said carriage and adjacent portions of the frame being provided with a plurality of opposed tracks, and an additional supporting connection for said carriage, positioned between said tracks, and anti-frictional means associated with said tracks and with said additional connection, adapted to maintain a three-point support of the carriage upon the frame.

2. In a track working machine, a frame adapted to span the rails of a track, rail engaging wheels at each side of said frame, a power source mounted on said frame, a grinding element and a driving connection between said element and said power source, and a carriage for said grinding element, said carriage being mounted for movement upon said frame, said carriage and adjacent portions of the frame being provided with a plurality of opposed tracks, and an additional supporting connection for said carriage, positioned between said tracks, and anti-frictional means associated with said tracks and with said additional connection, adapted to maintain a three-point support of the carriage upon the frame, and means for normally urging the carriage downwardly against the frame.

3. In a track working machine, a frame adapted to span the rails of a track, rail engaging wheels at each side of said frame, a power source mounted on said frame, a grinding element and a driving connection between said element and said power source, and a carriage for said grinding element, said carriage being mounted for movement upon said frame, said carriage and adjacent portions of the frame being provided with a plurality of opposed tracks, and an additional supporting connection for said carriage, positioned between said tracks, and anti-frictional means associated with said tracks and with said additional connection, adapted to maintain a three-point support of the carriage upon the frame, and means for normally urging the carriage downwardly against the frame, including rollers engaging portions of the carriage adjacent said tracks, guiding and supporting means for said rollers mounted on the frame and yielding means for urging said rollers downwardly against the carriage.

4. In a track working machine, a frame adapted to span the rails of a track, rail engaging wheels at each side of said frame, a power source mounted on said frame, a grinding element and a driving connection between said element and said power source, and a carriage for said grinding element, said carriage being mounted for movement upon said frame, said carriage and an adjacent portion of the frame being provided with opposed tracks, roller members intermediate said tracks, and yielding means for normally urging the carriage tracks downwardly toward the frame tracks and against said roller members, including thrust members guided on the frame, rollers associated therewith and engaging the upper side of the carriage track members and means for urging said rollers normally downwardly against said carriage track members.

5. In a track working machine, a frame adapted to span the rails of a track, rail engaging wheels at each side of said frame, a power source mounted on said frame, a grinding element and a driving connection between said element and said power source, and a carriage for said grind-

ing element, said carriage being mounted for movement upon said frame, said carriage and an adjacent portion of the frame being provided with opposed tracks, roller members intermediate 5 said tracks, and yielding means for normally urging the carriage tracks downwardly toward the frame tracks and against said roller members, including thrust members guided on the frame, rollers associated therewith and engaging the 10 upper side of the carriage track members and means for urging said rollers normally downwardly against said carriage track members, said rollers being generally aligned with the roller members between the tracks.

15 6. In a track working machine, a frame adapted to span the rails of a track, rail engaging wheels at each side of said frame, a power source mounted on said frame, a grinding element and a driving connection between said element and 20 said power source, and a carriage for said grinding element, said carriage being mounted for movement upon said frame, and means for moving said frame along the track, including manual handles associated with the rail engaging 25 wheels, said handles including arcuate hand engaging portions generally concentric with the axes of rotation of the wheels.

7. In a track working machine, a frame adapted to span the rails of a track, a plurality of 30 wheels on each side of said frame, adapted to engage the rails of said track, a power source mounted on said frame, a grinding element and a driving connection between said grinding element and said power source, and a carriage, upon 35 which said grinding element is mounted, said carriage being mounted for transverse movement upon said frame, and an arm, rotatably mounted on said carriage, said grinding element being rotatably mounted upon said arm, means for adjusting 40 said arm including a segmental gear axially spaced from said arm and at an angle thereto, means for holding gear and arm against relative rotation, a pinion in mesh with said gear, and manual means for rotating said pinion, and yielding take-up means for the play of gear and 45 pinion.

8. In a track working machine, a frame adapted to span the rails of a track, a plurality of 50 wheels on each side of said frame, adapted to engage the rails of said track, a power source mounted on said frame, a grinding element and a driving connection between said grinding element and said power source, and a carriage, upon 55 which said grinding element is mounted, said carriage being mounted for transverse movement upon said frame, and an arm, rotatably mounted on said carriage, said grinding element being rotatably mounted upon said arm, means for adjusting 60 said arm including a segmental gear axially spaced from said arm and at an angle thereto, means for holding gear and arm against relative rotation, a pinion in mesh with said gear, manual means for rotating said pinion, yielding take-up means for the play of gear and 65 pinion, and means for adjusting the effective length of the arm.

9. In a track working machine, a frame adapted to span the rails of a track, a plurality of 70 wheels on each side of said frame, adapted to engage the rails of said track, a power source mounted on said frame, a grinding element and a driving connection between said grinding element and said power source, and a carriage, upon 75 which said grinding element is mounted, said carriage being mounted for transverse movement

upon said frame, said carriage and an adjacent portion of the frame being provided with opposed contacting members adapted to maintain a three-point contact between carriage and frame, including two contact points, one adjacent each side of the carriage and adjacent one side of the frame, and a third contact point interposed between the front and rear of the carriage and intermediate the sides of the frame, the three points being sufficiently widely spaced to provide a firm support 10 for the carriage as a whole.

10. In a track working machine, a frame adapted to span the rails of a track, a plurality of 15 wheels on each side of said frame, adapted to engage the rails of said track, a power source mounted on said frame, a grinding element and a driving connection between said grinding element and said power source, and a carriage, upon 20 which said grinding element is mounted, said carriage being mounted for transverse movement upon said frame, said carriage and an adjacent portion of the frame being provided with opposed contacting members adapted to maintain a three-point contact between carriage and frame, including two contact points, one adjacent each side of the carriage and adjacent one side of the frame, and a third contact point interposed between the front and rear of the carriage and intermediate the sides of the frame, the three points being sufficiently widely spaced to 25 provide a firm support for the carriage as a whole, and roller means positioned at such contact points.

11. In a track working machine, a frame adapted to span the rails of a track, a plurality of 30 wheels on each side of said frame, adapted to engage the rails of said track, a power source mounted on said frame, a grinding element and a driving connection between said grinding element and said power source, and a carriage, upon 35 which said grinding element is mounted, said carriage being mounted for transverse movement upon said frame, said carriage and an adjacent portion of the frame being provided with opposed contacting members adapted to maintain 40 a three-point contact between carriage and frame, including two contact points, one adjacent each side of the carriage and adjacent one side of the frame, and a third contact point interposed between the front and rear of the carriage and 45 intermediate the sides of the frame, the three points being sufficiently widely spaced to provide a firm support for the carriage as a whole, and roller means positioned at such contact points, and a plurality of pairs of opposed tracks on said 50 carriage and frame adjacent the first two of said contact points, said rollers being interposed between such tracks.

12. In a track working machine, a frame adapted to span the rails of a track, a plurality of 55 wheels on each side of said frame, adapted to engage the rails of said track, a power source mounted on said frame, a grinding element and a driving connection between said grinding element and said power source, and a carriage, 60 upon which said grinding element is mounted, said carriage being mounted for transverse movement upon said frame, said carriage and an adjacent portion of the frame being provided with opposed contacting members adapted to maintain a three-point contact between carriage and frame, including two contact points, one adjacent each side of the carriage and adjacent one side of the frame, and a third contact point interposed between the front and rear of the car- 65 70 75

riage and intermediate the sides of the frame, the three points being sufficiently widely spaced to provide a firm support for the carriage as a whole, and roller means positioned at such contact points, and yielding means tending normally to urge said carriage downwardly toward said frame.

13. In a track working machine, a frame adapted to span the rails of a track, a plurality of wheels on each side of said frame, adapted to engage the rails of said track, a power source mounted on said frame, a grinding element and a driving connection between said grinding element and said power source, and a carriage, upon which said grinding element is mounted, said carriage being mounted for transverse movement upon said frame, said carriage and an adjacent portion of the frame being provided with opposed contacting members adapted to maintain a three-point contact between carriage and frame, including two contact points, one adjacent each side of the carriage and adjacent one side of the frame, and a third contact point interposed between the front and rear of the carriage and intermediate the sides of the frame, the three points being sufficiently widely spaced to provide a firm support for the carriage as a whole, and roller means positioned at such contact points, and yielding means tending normally to urge said carriage downwardly toward said frame, and means for adjusting the thrust of said yielding means.

14. In a track working machine, a frame adapted to span the rails of a track, a plurality of wheels on each side of said frame, adapted to engage the rails of said track, a power source mounted on said frame, a grinding element and a driving connection between said grinding element and said power source, and a carriage, upon which said grinding element is mounted, said carriage being mounted for transverse movement upon said frame, said carriage and an adjacent portion of the frame being provided with opposed contacting members adapted to maintain a three-point contact between carriage and frame, including two contact points, one adjacent each side of the carriage and adjacent one side of the frame, and a third contact point interposed between the front and rear of the carriage and intermediate the sides of the frame, the three points being sufficiently widely spaced to provide a firm support for the carriage as a whole, and roller means positioned at such contact points, and yielding means tending normally to urge said carriage downwardly toward said frame, including rollers engaging portions of said carriage upwardly spaced above said contact points, and means for maintaining a yielding thrust of said rollers downwardly against the carriage, while permitting movement of the carriage.

HENRY H. TALBOYS. 30
